US00D662362S

(12) **United States Design Patent**
Bickert et al.

(10) **Patent No.:** **US D662,362 S**
(45) **Date of Patent:** **** Jun. 26, 2012**

(54) **CUP**

(75) Inventors: **Robert Bickert**, Mobile, AL (US);
Mark Eyman, Chicago, IL (US)

(73) Assignee: **EBSCO Industries, Inc.**, Birmingham,
AL (US)

(**) Term: **14 Years**

(21) Appl. No.: **29/393,720**

(22) Filed: **Jun. 8, 2011**

Related U.S. Application Data

(63) Continuation-in-part of application No. 29/392,401,
filed on May 20, 2011.

(51) **LOC (9) Cl.** **07-01**

(52) **U.S. Cl.** **D7/510**

(58) **Field of Classification Search** D7/510,
D7/511, 500, 532, 900, 507; 215/121, 382,
215/388, 387; 220/674, 715, 713, 718, 592.16,
220/592.17, 709, 708; D9/529, 500, 539

See application file for complete search history.
